UNITED STATES PATENT OFFICE.

HUNTLEY N. SPAULDING, OF ROCHESTER, NEW HAMPSHIRE, ASSIGNOR TO J. SPAULDING & SONS CO., OF ROCHESTER, NEW HAMPSHIRE, A COPARTNERSHIP COMPRISING EMMA C. SPAULDING AND MARION L. SPAULDING, BOTH OF BOSTON, MASSACHUSETTS, ROLAND H. SPAULDING AND HUNTLEY N. SPAULDING, BOTH OF ROCHESTER, NEW HAMPSHIRE, AND LEON C. SPAULDING, OF BUFFALO, NEW YORK.

INSOLE.

Specification of Letters Patent.

Patented Apr. 13, 1915.

Application filed May 12, 1914. Serial No. 838,164.

To all whom it may concern:

Be it known that I, HUNTLEY N. SPAULDING, a citizen of the United States, and a resident of Rochester, in the county of 5 Strafford and State of New Hampshire, have invented an Improvement in Insoles, of which the following description, in connection with the accompanying drawings, is a specification, like characters on the 10 drawings representing like parts.

This invention relates to an inner sole for boots and shoes, by means of which a boot or shoe may be produced which is of superior quality and possesses advantages not 15 present in the highest grade of boots or shoes now found on the market, yet which can be made at a materially less cost and at substantially the same cost as the inferior grades of boots and shoes. To this end, the 20 boot or shoe, which may be a welted or other make of boot or shoe, is provided with an inner sole of material which is substantially non-stretchable, is firm yet flexible after long use, does not crack, curl or become hard 25 or disintegrate under the influence of moisture and dryness under conditions of use, and can be manipulated to enable it to be used in a welted shoe as well as in a turned or other make of shoe. A material suitable 30 for this purpose is a product composed in whole or in part of cotton rags which are chemically treated to render the same substantially hard, non-stretchable and non-compressible, and is then treated to render 35 the same flexible or pliable and not injuriously affected by moisture or dryness, under conditions of use. Such product will be hereinafter referred to as a flexible, substantially non-stretchable, chemically treated 40 fiber. An inner sole made of this product may be used in a welted shoe or any other kind of shoe, and when used in a welted shoe, it is channeled and provided with a lip extended at an angle thereto within the outer 45 edge of the inner sole and provided with corrugations or crimps to take up the surplus stock, and said corrugated or crimped lip may be reinforced by a layer of canvas or like material.

50 The particular features of this invention

will be pointed out in the claims at the end of this specification.

Figure 1 is a plan of an inner sole embodying this invention. Fig. 2, a plan of the inner sole shown in Fig. 1 with the canvas layer omitted. Fig. 3, a detail on an enlarged scale in plan to show the corrugated lip. Fig. 4, a side elevation of Fig. 3. Fig. 5, a section on the line 5—5, Fig. 3, and Fig. 6, a plan of a blank or plain inner sole 60 from which the channeled inner sole shown in Fig. 2 is made.

Referring to Figs. 1 and 2, *b* represents an inner sole having the lip *c*, which is reinforced by a layer or covering *d* of canvas 65 or like material, said inner sole being adapted to be used in a welted boot or shoe. The inner sole *b* is composed of a material which is substantially non-stretchable and non-compressible, is firm yet flexible after long 70 use, does not rot or deteriorate after long use, does not check or crack, curl or become hard or disintegrate under the influence of moisture and dryness under conditions of use, and is pliable to respond to the movements of the shoe in use, and presents a 75 surface to the foot of the wearer which remains smooth, firm and capable of resisting friction for a substantially long time. A material possessing these properties and 80 characteristics is composed of cotton rags alone or mixed with other materials and chemically treated with zinc chlorid or sulfuric acid to produce a substantially hard fiber in which the fibers are bonded together 85 by the partial solution of the fibers by the zinc chlorid or other solvent of cellulose, which in the case of the zinc chlorid is subsequently washed out of the fiber after the bonding of the fibers has been effected. The 90 hard fiber thus produced is then chemically treated by calcium chlorid, glycerin or other material to render the hard fiber flexible and pliable. This product, which will be hereinafter referred to as flexible, substantially non-stretchable, chemically treated 95 fiber, has been used heretofore for packing valves and other uses, but so far as I am aware, has never been used as an inner sole in the manufacture of boots and shoes. In 100

accordance with this invention, an inner sole of this material may be incorporated in a boot or shoe with material advantages, as will be described, and may be used in a welted or other make of shoe.

When an inner sole of the flexible non-stretchable chemically treated fiber is to be used in a welted shoe, an inner sole blank, 20 shown in Fig. 6, which is suitable for use in other kinds of shoes than welted shoes, is cut by dies or is otherwise formed from a sheet of the flexible, substantially non-stretchable, chemically treated fiber, and is channeled in the usual way to form the feather 21 and lip *c*, which latter is corrugated or crimped preferably transversely, so as to take care of the surplus stock in the lip, which is substantially non-compressible, and allow the latter to be given a position substantially at right angles to the under surface of the inner sole. The corrugations or crimps 23, are preferably made wider at the upper or free edge of the lip, and taper toward but not to the bottom or lower portion of the lip as shown in Fig. 4.

The crimped lip *c* may and preferably will be reinforced by a covering *d* of canvas or like material, which preferably forms part of a layer 25 of canvas, which is cemented to the under surface of the inner sole *b* within and outside of the lip *c*, and the portion of the layer covering the lip is cemented thereto. The reinforced lip responds to the machine, not shown, but such as is now commonly used in the manufacture of reinforced inner soles, and can have its free edge bent inwardly and thereby insure that the reinforced corrugated lip is in a substantially vertical position with relation to the body portion of the inner sole and in proper position for sewing to the upper of the shoe.

The inner sole of flexible, substantially non-stretchable, chemically treated fiber, is capable of being used in the manufacture of boots and shoes, with the machines now commonly used, and is capable of materially reducing the cost of the higher or medium grades of shoes, in which leather inner soles have heretofore been used, and in addition enables a superior boot or shoe to be produced at a materially less cost. By reason of the fact that the inner sole is non-stretchable or substantially so, the shoes of a given width run uniform and are of the same width, inasmuch as the non-stretchable fiber resists the stretching action of the inseam stitches and prevents the shoe being widened in the process of stitching the upper to the inner sole, which stretching occurs when the inner sole is of leather, as the leather inner soles used in the same grade and width of shoes, vary in strength and some are more stretchable than others, so that, it frequently happens that with the same grade and width

of leather inner soles, the shoes, which are supposed to be of the same width, differ materially in width which is not desired by the manufacturers. Furthermore, when a reinforced leather inner sole is used, it sometimes happens, that when the upper is sewed to the inner sole, the leather of the reinforced inner sole will stretch to such extent as to place all the strain on the canvas layer of the reinforced inner sole, with the result that the latter is split lengthwise of the inner sole, and in these cases, a defective shoe would result, which is avoided by the operator pulling the shoe to pieces, discarding the inner sole and replacing it with a new one, which not only occasions delay but adds to the cost of manufacture. So also in the higher grades of shoes in which leather inner soles are used, when the leather is of such nature that it is unable to resist the lateral strain placed upon it by the machine which sews the upper and welt to the inner sole, the latter will stretch to such extent as to arch or transversely curve the inner sole and bend the welt. When this occurs, the shoe is taken off of the last and the welt is bent back into shape by hand, and the arch in the inner sole is pressed down in the subsequent processes of manufacture through which the shoe passes, but inasmuch as the leather has been once stretched, the arch is subsequently restored when the shoe is worn and a bulge at the center of the inner sole is formed, which is highly objectionable to the wearer of the shoe. Furthermore by reason of the fact that the leather inner soles are stretchable more or less, the lines of the shoe are more or less distorted from those on which the manufacturer desires that the shoes should be built.

The above noted defects in boots or shoes provided with leather inner soles, are avoided by the use of an inner sole of flexible substantially non-stretchable, chemically treated fiber herein described, which resists the lateral strain placed upon it by the machine which sews the upper to the inner sole, and consequently all the shoes of a given width are of the same or uniform width and free from bulges in the inner sole within the shoe. Another feature of superiority in a boot or shoe provided with the flexible non-stretchable, chemically treated fiber over a boot or shoe provided with a leather inner sole, is that the boot or shoe provided with the chemically treated fiber inner sole has a smooth, firm surface for contact with the foot for substantially the life of the shoe, whereas, a boot or shoe provided with a leather inner sole, when worn by a person whose feet perspire freely, soon become unfit to wear, owing to the fact that the leather inner sole absorbs the moisture from the feet while the shoe is being worn, and when the shoe is removed, the inner sole becomes dry,

and as this takes place daily, the leather inner sole soon loses its flexibility, becomes hard and more or less like bone, and cracks, especially at the ball portion, and these 5 cracks form rough and frequently sharp edges, which soon make the foot tender and sore, to such extent that the shoes have to be discarded long before they are worn out at the outer sole or upper. Furthermore the 10 leather inner sole curls at the edges and forms hard projections within the shoe which are highly objectionable. A boot or shoe provided with the inner sole of flexible non-stretchable, chemically treated fiber, is 15 not open to these objections, inasmuch as the chemically treated fiber inner sole is not injuriously affected by moisture and dryness, under conditions of use, does not curl, crack or become hard but retains its flexibility, 20 and enables the boot or shoe to be worn without discomfort by persons whose feet perspire freely. Furthermore the chemically treated fiber inner sole is not disintegrated by moisture and friction.

25 The chemically treated fiber inner sole herein described, is materially cheaper than a leather inner sole, and not only reduces the cost of manufacture of the high grades of boots or shoes, but also materially improves 30 the same, in that it provides the boot or shoe with an inner sole, which imparts to the sole portion of the shoe a permanent flexibility, softness, smoothness and firmness of

surface for contact with the foot of the wearer, and enables the shoe to be worn with 35 comfort for the life of the shoe, and also insures to the manufacturer uniformity in width and outline of the shoes, durability and reduced cost in the manufacture of the same.

Claims:

1. An inner sole of flexible, substantially non-stretchable chemically treated fiber in which the fibers of the inner sole are bonded together by a partial solution of the fibers 45 themselves.

2. An inner sole of flexible, substantially non-stretchable and non-compressible chemically treated fiber in which the fibers of the inner sole are bonded together by a partial 50 solution of the fibers themselves, said inner sole having a lip extended at an angle thereto within the outer edge of the inner sole and provided with corrugations to take care of the surplus material of the substantially 55 non-compressible lip and enable the inner sole to be used in a welted boot or shoe, substantially as described.

In testimony whereof, I have signed my name to this specification in the presence of 60 two subscribing witnesses.

HUNTLEY N. SPAULDING.
